ATTORNEY

UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

REVERTIVE TEST SYSTEM.

Application filed April 9, 1919. Serial No. 288,781.

To all whom it may concern:

Be it known that I, WINFRED T. POWELL, a citizen of the United States, residing in Rochester, in the county of Monroe and State of New York, have invented certain new and useful Improvements in Revertive Test Systems, of which the following is a full, clear, concise, and exact description.

This invention relates to telephone systems, and more particularly to such systems of the central energy type in which the busy or idle condition of a telephone line is determined by the presence or absence of a definite potential at the test terminals of the line switching terminals in which the lines terminate.

My invention has a particular application in connection with a semi-automatic telephone system, although it is not limited to such use as there is a large and extensive demand for such a system as is herein illustrated and described in connection with manual and semi-automatic telephone systems.

In manual and semi-automatic systems it is very often desirable to supply an operator with information automatically given as to the particular line upon which the calling subscriber is located for instance, connection with the giving of toll service. The securing of such information enables charges to be made to the correct party who secures the service. Such a use of my invention is provided for in the embodiment illustrated and described herein, and means are provided for the operator to check the correctness of the information given by the subscriber as to his line number.

Also a use of my invention will be described herein where an additional object of my invention is secured, namely, of advising the operator whether the called-for subscriber is on the same line as the calling subscriber.

In both uses of my invention as herein illustrated, special means are provided by which an operator will obtain a distinctive signal when in testing a multiple terminal of a calling line which is different from the signal secured when the operator tests a multiple terminal of a different called line. It is found in the systems of the art which produce a musical note or tone in the receiver of the testing operator whenever the

terminals of the line upon which the calling subscriber is located are tested, that this tone is apt to confuse the operator since there are many other tones used in telephone exchanges, particularly where automatic equipment is used, such as trouble tones, wrong number tones, etc., and the result is with such systems of the prior art that the operator often concludes that the tested terminals are associated with the line upon which the calling subscriber is located, and if the operator is a toll operator, the tone being used as a checking tone, the operator sometimes allows the subscriber to make a long distance call, charging the expense of the toll service to whatever line number the subscriber wrongly may give.

In the system of my invention, however, the apparatus thereof is so organized that a battery click will be heard if the tested terminals of the called-for line belong to the line to which the calling subscriber is located, and a tone is heard when testing any other called-for line if the said called-for line is busy, nothing being heard if the said other called-for line is idle. In using my invention in connection with a toll checking system the operator encountering such a tone as might be confused with the busy tone, the error would not cause her to put through the long distance call and to make the charge to the telephone line or the line number the subscriber may wrongly give.

Other objects of my invention and the invention itself will be better understood from the description of the same which follows in which—

Fig. 1 and Fig. 2 when placed together make a complete drawing of a system of my invention as will be necessary in order to instruct those skilled in the art as to the construction and operation of the same.

In Figs. 3 and 4 schematic diagrams are illustrated to show the flow of currents in the several circuit branches under the different operative conditions produced in the operation of the system of my invention.

The system of my invention is illustrated in Figs. 1 and 2 as a calling line number checking system.

Referring to Fig. 1, at A I show a calling sub-station having a line switch LS, by means of which the calling substation is connected to an interconnecting link circuit LK

which in turn is adapted by the operation of its switch wipers *a*, *b* and *c* to extend a connection to a trunk circuit *TK*, illustrated in Fig. 2.

5 A signal lamp *s* is illustrated for the trunk circuit and adapted to operate when a call from a calling line seizes the trunk circuit *TK* to announce the call to the toll operator having an interconnecting cord circuit *CD*, which preferably would be one of a plurality of cord circuits and which operator would also have an operator's set *O*, which preferably would be common to the said plurality of cord circuits.

10 15 A test terminal *TT* of the calling line is extended from a conductor associated with the line switching mechanism in order to enable the operator to make the checking line test, as will be hereinafter described.

20 25 Other test terminals *TT*² and *TT*³ are provided for another line which is assumed in this description to be a busy line and another line assumed to be an idle line respectively, a description being had of the conditions attending the testing of each kind of a line; reference being had therein to each of the terminals above referred to in such description.

30 35 The line with the substation A is illustrated in Fig. 1 as having another substation B, as well, reference being had to the said other substation in that part of the description of the system of my invention which follows, which refers to the use of my invention in connection with party lines.

In Fig. 2 a substation N, is shown leading by line conductors to terminals associated with the test terminals *TT*³ above referred to as belonging to another idle line.

40 45 The cord circuit *CD* is illustrated as having the usual battery feed supervisory relays and supervisory signals in order to give the operator the usual supervisory control over the connection. At *TR*, I show a relay comprising an essential part of the combination of elements required to produce a system of my invention. This relay is illustrated and shown as a differential relay having two windings, the first of which when both windings are energized by current flowing through them opposes the action of the second and tends to neutralize the magnetic effect of the second upon the armatures of the relay. This relay might be constructed in various ways, it being only necessary that one of the windings opposes the effect of the first upon the relay contacts.

50 55 Referring now to the drawings, I will describe the operation of the embodiment of my invention first, when use is made of the system of my invention for interconnection with party lines to indicate to the operator when the calling line is identical with the called line, and second, a description will be had of the system of my invention when the

same is used as a toll operator's checking system.

Referring to Fig. 1, the subscriber at substation A, upon removing his receiver to initiate a call, completes an energizing circuit for the line relay *LR* of the individual line switch *LS* over the following circuit:—ground *G*, contact spring 1 of cut off relay *CO*, line conductor 2, primary induction coil *i*, switch hook contact 3, transmitter *t*, calling device *CD*, line conductor 4, contact 5 of cut off relay *CO*, and winding of line relay *LR* to the source of current. The line relay *LR* energizes and closes the following circuit:—ground *G*², contact 6 of relay *LR*, terminal 7 and wiper 8 of line switch *LS*, contact 9 of relay *CO*, contact 10 of line switch stepping magnet *ST* and winding of line switch stepping magnet to the source of current. The stepping magnet energizes, breaks its own circuit at contact 10 and, as the armature retracts, the wipers 8, 11, 12 and 13 are advanced one step in the well known manner, which brings them to rest on the second row of terminals to which are multiplied the trunk wires leading to a selector circuit like *LK*. Assuming this trunk to be busy at this time, there will be a connection to ground on terminal 14, placed there by the line switch which is holding this trunk busy, the manner in which this is done will be seen when the point is reached in this description where the selector *LK* is seized and made busy. This ground now found on terminal 14 will flow over wiper 8, contact 9, contact 10 and the winding of magnet *ST* to the source of current, again causing the line switch to step in the same manner as before which brings the wipers 8, 11, 12 and 13 to rest on the third row of terminals. This row, like the first row, is a "home point" and, as the circuit condition is the same at all "home points," the wipers will again be advanced in the same manner as described for the first step. The wipers are now resting on the fourth row of terminals which is assumed to be the multiple of an idle trunk.

The following circuit is now closed to operate the cut off relay *CO*:—ground *G*³, resistance coil 15, normally made off normal contact 16, contact 17 of selector secondary stepping magnet *SM*, terminal 18 and wiper 12 of line switch *LS*, winding of relay *CO*, contact 10 and winding of line switch stepping magnet *ST* to the source of current. It will be noted that a ground like *G*³ was also on terminal 19 as wiper 12 passed it but this ground could not operate relay *CO* because it was short circuited by the ground which was on terminal 14 for making the trunk busy.

The cut off relay *CO*, now energizes, disconnects the battery bridge from the line at contacts 1 and 5 and extends line conductor

2 by way of contact 20, wiper 13, terminal 22, contact 23 of selector "cut through" relay CT, winding 24 of selector impulse relay IMP to ground G⁵. Line conductor 4 is also 5 extended by way of contact 21, wiper 11, terminal 25, contact 26 of relay CT and winding 27 of relay IMP to the source of current. The line switch cut off relay CO also closes the following circuit for making 10 the selected trunk test busy to other line switches: ground G⁴, contact 28, wiper 8 and the multiple of terminal 29 appearing at all other line switches having access to this selector.

15 Relay IMP of selector LK upon energizing, closes a circuit from ground G⁵, contact 30, and winding of the holding relay H to the source of current. Relay H energizes and closes contact 31 which holds the ground 20 G³ on the holding trunk 32 as long as this selector is held by relay IMP. The original circuit to the holding trunk was traced through off normal contacts 16 but as this contact opens upon the first step of the selector, the above traced substitute path is provided.

The foregoing operations have all been brought about by the removal of the receiver *r* at the substation. Assume now that 30 the selector LK has access to several levels, each of which contains trunks leading to an operator handling different classes of service.

First will be described the operation of 35 what is known as a revertive call, i. e., when the subscriber at substation A asks the operator to connect him with number 1234, for instance, which number belongs to the subscriber at substation B who is on the 40 same line with A.

The subscriber at substation A now operates the dial CD in accordance with the digit which corresponds to the position of the required set of contacts in the bank of 45 the selector, thereby breaking the continuity of the loop a number of times by the opening and closing of the dial impulse springs in the well known manner. As a result of these interruptions the impulse relay IMP 50 is deenergized a corresponding number of times, sending an impulse at each deenergization from ground G⁵ to the slow acting relay CH and the primary stepping magnet PM in series by way of contacts 33, 34 and 55 35. While these impulses are being sent by relay IMP, relay H being slow acting, remains in its operated position. The primary stepping magnet PM is operated at each deenergization of relay IMP and steps 60 the shaft carrying wipers *a*, *b* and *c* to the required level or row of contacts. Relay CH, being slow acting, retains its armature in the operated position during the series of impulses and closes a circuit for the test 65 relay T, as follows: ground G⁶, contact 36

of relay CH, and winding of relay T to the source of current. Relay T locks over the following circuit: ground G³, resistance coil 15, contact 31 of relay H, contact 17 of magnet SM, off normal contact 40, contact 38 of relay T and winding of relay T to the source of current. At the end of the series of impulses the relay CH deenergizes, thereby completing the circuit for the secondary stepping magnet SM from ground G³, low 70 resistance coil 15, contact 31 of relay H, contact 17 of magnet SM, off normal contact 40, contact 38 of relay T, contact 37 of relay CH, contact 41 of magnet SM, and winding of SM to the source of current. The magnet SM operates, advances the wipers *a*, *b* and *c* one step on to the first set of contacts and breaks its own circuit at contact 41 allowing the armature to retract. All trunks in this level which are busy will have 80 grounds on the terminals like 42, which grounds will cause relay T to remain energized from ground on these terminals 42, wiper *b*, contact 38 of relay T and the winding of relay T to the source of current. 85

The switch shaft and wipers will be advanced past all these busy trunks by means of the following circuits:—ground on the terminal 42, wiper *b*, contact 38 of relay T, contact 37 of relay CH, contact 41 and winding of magnet SM to the source of current. As soon as the wipers reach a trunk which has no ground on the test terminal like 42, magnet SM will not again energize and relay T will deenergize. The test relay 90 T, upon deenergizing, completes a circuit for the "cut through" relay CT, from ground G³, resistance coil 15, contact 31 of relay H, contact 17 of magnet SM, off normal contact 40, contact 39 of relay T, and the winding 95 of relay CT to the source of current. Relay CT energizes, disconnects the line conductors 49 and 44 from the battery bridge relay IMP at contacts 23 and 26 and extends the line conductors 49 and 44 by way of contacts 45 and 46 and wipers *a* and *c* to the trunk line conductors 47 and 48 leading to the trunk circuit TK. A circuit is now closed from ground G⁷, contact 50 of trunk circuit cut off relay TC, trunk wire 47, 100 105 closed circuit of substation A; trunk wire 48, contact 51 of relay TC and the winding of the trunk line relay TL to the source of current.

Relay TL now energizes and closes a circuit from ground G⁸, contact 53 of relay TL, 110 resistance coil 55, trunk wire 43, wiper *b* of selector LK, contact 39 of relay T and winding of relay CT to the source of current.

This circuit is closed before relay H of 115 the selector releases, therefore this substitute ground for holding relay CT is applied before the original one is opened at contact 31 of relay H. Relay TL also closes a circuit from ground G⁸, contact 52 of relay TL 120 125 130

and the signal lamp S to the source of current. (The wire from lamp S may lead to the source of current through a pilot relay or be connected direct as desired).

- 5 The operator, in response to this signal, inserts the answering plug AP in the jack AJ, whereupon the following circuit is closed to energize relay TC:—ground G⁹, winding of sleeve relay S, sleeve 56 of plug AP, sleeve 57 of jack AJ and winding of relay TC, to the source of current. Relay TC opens the trunk circuit battery bridge at contacts 50 and 51 and the calling substation will be fed talking battery through 10 the windings of answering supervisory relay AS by way of the tip and ring contacts of the plug and jack.

Relay TL now releases and breaks the holding ground circuit for the selector at 20 contact 53 but not until another substitute ground has been established from ground G⁹, winding of relay S, sleeve 56 of plug AP, sleeve 57 of jack AJ, contact 54 of relay TC to the holding trunk 43. Relay TL, 25 releasing, also extinguishes the signal lamp S by opening contact 52.

The operator now operates the listening key LT associated with the cord circuit used and receives the request of the calling party 30 in the well known manner, after which she tests the called line multiple by touching the tip 64 of the calling plug CP to the sleeve TT, TT² or TT³ which represents the sleeve jack of the calling line, of another busy line 35 and an idle line respectively. If the called for line is idle there will be no difference of potential established when this test is made, the circuit on the sleeve of the tested jack going to main battery as shown at IL. 40 The operator will then insert the plug CP into the jack IL and ring the bell of the called party by operating the ringing key RK which applies ground G¹¹ to the tip conductor 69 and generator G¹², G¹³, G¹⁴ or 45 G¹⁵ (depending on the frequency required which is selected by the operator depressing one of the keys 65, 66, 67 or 68) to the ring conductor 70 of the called line. Upon response of the called party at substation N 50 a direct current path is closed through the transmitter 71 and the primary induction coil 72. This closed circuit operates the calling supervisory relay CS, through which relay is fed the talking battery for station N. Talking battery for the calling station 55 A is fed through relay AS and the two paths are connected together by condensers 73 and 74. When the conversation is completed, the called party at substation N hanging up 60 the receiver deenergizes relay CS which causes the calling supervisory lamp SI to burn and the calling party at substation A hanging up the receiver deenergizes relay AS which causes the answering supervisory 65 lamp SG to burn. The operator now with-

draws both plugs AP and CP from the jacks which causes the selector LK and the line switch LS to release in a manner to be later described.

Assume now that the called line is busy 70 when the operator touches the tip 64 of the cord to the sleeve of the jack. The circuit condition of the sleeve of a busy line is shown at BL where CO' represents the resistance of cut off relay CO and the line 75 switch stepping magnet ST in series and SL' represents the resistance of sleeve relay S or SL of the cord circuit to which this line is connected. If a calling line has not yet been answered, resistance CO' represents either resistance coil 15 or 55 depending on the distance which the call has progressed. When the operator makes this test the following circuit is closed: ground G¹⁶, coil winding SL', sleeve TT² of jack 80 BL, tip 64 of plug CP, contact 81 of relay SL, common test wire 82 and winding 75 of relay TR to the source of current. Relay TR energizes and closes contact 77, which places the tip of the plug 64 in series 85 with winding 76 of relay TR into connection with the sleeve of the calling line by way of common wire 84 and contact 85 of listening key LT. This circuit condition is shown schematically in Fig. 4 where the 90 same reference numbers are used in connection with corresponding parts of the circuit in Fig. 1 and Fig. 2. Thus it will be seen that relay TR gets current through winding 75 when it is energized and that, when contact 77 is closed, current also traverses winding 76 which winding is wound on the core of relay TR in a direction opposite to winding 75. This immediately deenergizes relay TR, opens contact 77 when relay TR 100 will again energize. This action continues which produces a buzzing tone in the operator's receiver by opening and closing the circuit across impedance coil MP and connecting condenser 80 thereto. This buzzing 105 tone indicates to the operator that the called for line is busy, she so informs the calling subscriber who hangs up the receiver and she then withdraws the answering plug AP. This disconnects ground G⁹ from the sleeve 110 57 of the jack AJ, allows relay TC to deenergize and as there is now no ground on the holding trunk 43, relay CT of selector LK and relay CO of line switch LS both deenergize.

Relay CT closes the following release circuit for the selector LK: ground G⁵, contact 33 of relay IMP, contact 34 of relay CT, contact 58 of relay H, off normal contact 59 and winding 60 of release magnet 115 REL. Magnet REL, in addition to releasing the selector LK in the well known manner, closes a circuit from ground G¹⁰, contact 62 of magnet REL, low winding 61 of magnet REL, trunk wire 63, line switch ter- 120 125 130

for the said link circuit, an operator's receiver for the said operator's set, a test circuit associated with the said operator's receiver and the said link circuit, means to produce a battery "click" audible busy tone in the operator's receiver when a test is made of a test terminal of the same line to which the answering terminals of the link circuit are already connected, and means to associate a tone producing source of current with the said operator's receiver instead of the said battery click source of current if the tested terminal of the called-for line is a different line than that already connected to the link circuit by said answering terminals and said answering line jack terminals.

3. In a telephone system, the combination with a plurality of telephone lines, a line interconnecting link circuit, an operator's set adapted to be associated with the said link circuit, test terminals for each of the lines, answering jack terminals for each of the lines and co-operating answering terminals for the said link circuit, an operator's receiver for the said operator's set, a test circuit associated with the said operator's receiver and the said link circuit, means to produce a battery "click" audible busy tone in the operator's receiver when a test is made of a test terminal of the same line to which the answering terminals of the link circuit are already connected, means to associate a tone producing source of current with the said operator's receiver instead of the said battery click source of current if the tested terminal of the called-for line is a different line than that already connected to the link circuit by said answering terminals and said answering line jack terminals, and disabling means for said battery "click" and said tone test means should the tested terminal of the called-for line be associated with a line different from that to which the link circuit is already connected, and which different line is in an idle or unused condition.

4. In a telephone system, the combination with a plurality of subscribers' lines, answering terminals and a plurality of multiple terminals for each line, means including a link circuit for establishing a connection for two of said lines, means in said link circuit for testing a busy line, a testing mechanism, and means for operating said testing mechanism when a terminal of the calling line to which the link circuit is already connected is tested to give the operator an audible busy signal of one character, and to give the operator an audible signal of another character when a terminal of a line other than the calling line is tested, when the said other line is in a busy condition, said testing mechanism comprising a differentially wound relay, one of the windings of which contains in its circuit normally open contacts of the said relay.

5. In a telephone system, an operator's cord circuit provided with a calling plug, a testing conductor normally associated with said plug, a relay winding in said testing conductor, a second relay winding, said windings being so connected in their respective circuits that the combined effect of current flowing simultaneously through the two windings is to disable the said relay, energizing circuits for both of the said windings under the control of said calling plug and testing conductor, and normally open contacts of said relay interposed in one of the said relay windings.

6. In a telephone system, an operator's cord circuit provided with a calling plug, a testing conductor normally associated with said plug, a relay winding in said testing conductor, a second relay winding, said windings being so connected in their respective circuits that the combined effect of current flowing simultaneously through the two windings is to disable the said relay, energizing circuits for both of the said windings under the control of said calling plug and testing conductor, and normally open contacts of said relay interposed in the second one of the said relay windings.

7. In a telephone system the combination with a central station, a plurality of telephone lines terminating thereat, a busy testing circuit, means for completing said circuit, a modifying circuit for the said busy testing circuit, and means to produce currents of different characteristics when said first circuit is closed, the operation of said means being controlled by the character of the said energizing circuit.

8. In a telephone system, the combination with a plurality of telephone lines, a main exchange switchboard, one of the telephone lines being a poly-station telephone line, a switchboard having answering terminals for the said poly-station telephone line, and a plurality of multiple terminals for said telephone line, a link circuit for the answering switchboard section, an operator's receiver adapted to be operatively associated with the said link circuit, tone producing means for energizing the operator's receiver to cause it to give distinctive audible signals, means to interconnect said link circuit with said answering line terminals, means to test a terminal of a desired called-for line, by causing a terminal of the said link circuit to contact therewith, and controlling means including a differential relay for said audible signal producing means to differently operate the said controlling means to cause a tone signal to be produced by the operator's receiver when the tested called line terminal is associated with a busy called line different from the line to which the link circuit has already been connected, and to cause a different kind of an audible

- signal to be produced by the said receiver when the tested terminal of the called-for line is associated with the line to which the link circuit has already been connected, said 5 audible signal producing means being inoperative to produce an audible signal in the operator's receiver when the tested terminal of the called-for line is associated with an idle or unused line.
- 10 9. In a telephone system, the combination with a central station, a plurality of telephone lines terminating thereat, a testing circuit, an operator's telephone receiver associated therewith, and means including a 15 differentially wound relay to produce a current of distinctive characteristics when said testing circuit is closed, the operation of said means being controlled by said circuit.
10. In a telephone system, the combination of a plurality of telephone lines, link 20 circuits for interconnecting said lines, an operator's telephone set arranged to be associated with the said link circuit, test terminals for each of said lines, a test circuit 25 and a differential relay associated with said link circuit, a locking circuit for said differential relay including one of its windings arranged to be maintained closed during the testing by said test circuit of the 30 terminals of a telephone line of one character and arranged to be intermittently closed during the testing of the terminals of a line of another character, and means controlled by said differential relay to distinctively 35 signal said operator's telephone set.
11. In a telephone system, the combination of a plurality of telephone lines, certain of said lines being poly-station lines, link circuits for interconnecting said telephone lines, an operator's position at which 40 said link circuits are located, a testing circuit, and a testing relay having two windings, one of said windings being energized during the testing of a busy line by said 45 test circuit, and the second of said windings being intermittently short circuited during the testing of one line and permanently short circuited during the testing of a poly-station line that has originated the call.
- 50 12. In a telephone system, a plurality of telephone lines, certain of said lines being provided with a plurality of sub-stations, an operator's position and a plurality of link circuits through which a calling tele-
- phone line is serially extended to said operator's position, said extended connection terminating in a manual switch, a test circuit including a double wound relay arranged to test a wanted line under the control of said manual switch, one of said windings being energized over a circuit including said test circuit during the testing of any busy line, the second of said windings being intermittently or permanently short circuited during the testing of a busy line dependent on the character of said line. 55
13. In a telephone system, a plurality of telephone lines of different character, means for characterizing telephone lines by a busy or idle condition, link circuits and numerical and non-numerical switches for extending a calling line to an operator's position, manual means for testing the condition of a wanted line, and means operative thereupon for indicating the character of the busy 70 line being tested.
14. In a telephone system, a plurality of telephone lines of different character, means for characterizing telephone lines by a busy or idle condition, link circuits and numerical and non-numerical switches for extending a calling line to an operator's position, means including a differential relay for testing a wanted line, and means operative 75 upon the actuation of said differential relay for indicating the character of a busy line tested.
15. In a telephone system, a plurality of telephone lines including main lines and poly-station lines, means for characterizing 80 said telephone lines by a busy or idle condition, a link circuit and numerical and non-numerical switches for extending a calling line to an operator's position, a test circuit including relay mechanism, and a manual 85 switch at said operator's position for extending said test circuit, said test circuit while testing a main called line being completed at said line, and in the case of a re-vertive call said test circuit extending serially through said link circuits and switches, and a signal controlled by said 90 test circuit and relay mechanism.
- In testimony whereof, I hereunto subscribe my name this 7th day of April, A. D. 1919.

WINFRED T. POWELL.
